UNITED STATES PATENT OFFICE.

JOHN F. BERRY AND WILLIAM E. BURRILL, OF BANGOR, MAINE.

CEMENT-BLOCK MACHINE.

1,143,490.

Specification of Letters Patent.

Patented June 15, 1915.

Application filed July 15, 1912. Serial No. 709,455.

To all whom it may concern:

Be it known that we, JOHN FRANCIS BERRY and WILLIAM EDMUND BURRILL, citizens of the United States, residing at Bangor, in the county of Penobscot and State of Maine, have invented certain new and useful Improvements in Cement-Block Machines, of which the following is a specification.

While we have illustrated our invention as especially adapted for the manufacture of cement blocks from which to form chimneys, it will of course be understood that hollow blocks for any purpose may be manufactured with this machine.

In the drawings:—Figure 1 is a front elevation of a cement block machine, embodying our invention; Fig. 2 is an end elevation; Fig. 3 is a top plan view; Fig. 4 is a section on the line 4—4, Fig. 3; Fig. 5 is a section on the line 5—5, Fig. 3; Fig. 6 is a vertical central section of a chimney constructed of blocks formed by our machine; Fig. 7 is a transverse section of Fig. 6; Fig. 8 is a top plan view of a modified form of mold; Fig. 9 is a sectional view similar to Fig. 4, showing a modified form of mold, and Fig. 10 is a sectional view similar to Fig. 5, showing a modified form of mold.

The supporting frame of our machine comprises standards 11 connected by cross-pieces 12, 13, 14 and 15.

16 is the platform supported by the frame.

The mold box may be formed of any desired number of sections, although I have shown the box formed of four sections 17, 18, 19 and 20, each section being provided with a perforated lug 21, through which a suitable bolt 22 passes to secure the sections together. Sections 17 and 19 are divided in vertical planes at their angles and the two members of section 19 are connected by hinges 23, so that the halves of the entire mold may be swung away from or toward each other by opening and closing the mold and facilitating the adjustment of the core. When closed, the hinging members of the mold are readily secured in position by the positioning pins hereinafter referred to. The mold may have any desired perimeter; for instance, it may be square, oblong, octagonal, etc. The mold sections are each provided with a bottom ledge 24, from which depends a rim 25, at the bottom of which is an inwardly extending flange 26, so that when the sections are brought together, there

is formed a recess 27 to be hereinafter referred to.

28 are removable planks constituting part of the platform of the machine on which the inwardly extending flanges 26 rest, thereby supporting the mold on said planks.

29 are positioning pins secured to the base flange 26 of the mold, to which are pivotally secured links 30, said links being in turn pivotally mounted on the levers 31. 65 These levers 31 are pivotally mounted at one end in a bracket 32 and provided at the other end with a handle 33.

34 is a rack bar secured to one of the standards 11 adapted to be engaged by the lever 31 and support the lever in its adjusted position, whereby the mold box is firmly clamped to the removable planks 28, thus insuring a tight joint between the flange 26 and said planks.

35 is a solid core adapted to be reciprocated in the mold and provided with a stem 36, from which depend links 37, said links being pivotally secured to the lever 38. The lever 38 is pivotally mounted at one end in a hanger 39 secured to the frame, while the forward end of the lever is deflected upwardly as at 40 and terminates in a grip portion 41 which is parallel with the main body of the lever.

42 is a rack bar mounted on one of the standards 11 adapted to be engaged by the lever 38 and hold the same in an adjusted position, whereby the solid core 35 is supported in its position. A sheet metal core 43 is arranged within the mold around the solid core 35, its lower edge extending to the plane of the upper face of the planks 28 and resting upon a casting 44 secured to the planks 28, whereby a sharp corner is formed 95 between the core 43 and the flange 26, as shown in Figs. 4 and 5. The upper edge of the sheet metal core is bent to form a face 45 and a flange 46 corresponding with the rim 25 and the base flange 26 of the 100 mold.

In Figs. 9 and 10, I have shown the mold formed with step-like ledges 47. This design of mold is adapted to form the cap block for the chimney. The interior surface of the mold may be ornamented to give any desired design to the finished product.

In using the machine to form cement blocks, the parts are assembled as best seen in Figs. 4 and 5, with the mold locked firmly

by the levers 31 on the removable planks 28, the solid core 35 elevated in the mold and locked in that position by the lever 38, and the sheet metal core in the mold 5 rounding the solid core with its lower edges snugly fitting on the castings 44. A reinforce 48 is now placed in the mold. The desired mixture of cement is now poured between the mold and the sheet metal core and 10 tamped as is usual in forming cement bodies, thus thoroughly embedding the reinforce in the composition and forcing the composition to take the shape of the mold. After the cement has set for a while, the solid 15 core 35 is withdrawn from the mold by the lever 38, while the sheet metal core is permitted to remain in the mold until the cement has thoroughly set, after which it is removed.

20 The depending arm 25 and the base flange 26 of the mold, as stated, form a recess 27 into which the cement composition is forced, thereby forming a tongue 49 on the bottom of the finished product, while the formation 25 of the top of the sheet metal core, as at 45 and 46, forms a depression or recess 50 in the top of the block, so that each completed block is provided with a tongue on its bottom face and a corresponding recess in its 30 top face, whereby when the blocks are brought together in a chimney structure as shown in Fig. 6, the blocks interlock by reason of the tongue of one block projecting into the recess of the other block. Before 35 the blocks are assembled, thin cement is placed in the recess in the top of the block, after which the tongue of the next succeeding block is placed in said recess, the liquid cement thoroughly uniting one block with 40 the other, thus eliminating all possible danger of fire or smoke passing through the joints between the blocks.

We claim:—

1. In a cement block machine, the combination with a frame, having a removable platform, of a mold mounted on said frame, said mold being divided along its diagonal vertical plane into two halves having hinged connection to permit the swinging of said 50 halves to remove the block, levers pivoted

to said frame and connected to said mold, and locking means for clamping the mold firmly on the platform, a solid core within said mold having a depending stem, a lever pivotally mounted to the frame and pivotally connected to said stem to control the position of the solid core relative to the mold, said platform being provided with an opening, a liner for said opening, a removable sleeve around said core, said sleeve being seated in said liner.

2. In a cement block machine for forming hollow blocks, the combination with a frame having a platform provided with an opening, of a mold formed in sections and having hinges permitting relative swinging of the sections for removing the block, said mold being provided with an inwardly tapering lower end with an opening in its bottom wall commensurate with the opening 70 in the platform, links depending from said mold bottom, and levers journaled on said frame and connected to said links, and locking means for the levers whereby the mold is clamped to the platform, a detachable sheet 75 metal core in said mold provided with an overhang at its upper end corresponding in shape to said tapering end, the lower end of the core extending through the opening in the bottom of the mold and through the opening in the platform and registering therewith, a solid movable core extending through the openings in said mold and platform and into the sheet metal core, a stem depending from said solid core, a link depending from and pivotally connected to said stem and a lever journaled on the frame and pivotally connected to and supporting said solid core, whereby the relative positions of the sheet metal core and the solid 80 core may be changed.

The foregoing specification signed at Bangor, Maine, this fourteenth day of June, 1912.

JOHN F. BERRY.
WILLIAM E. BURRILL.

In presence of two witnesses:

CHARLES F. SWEET,
A. B. SAWYER.
